UNITED STATES PATENT OFFICE.

GUSTAF H. EKSTROM, OF ROCKFORD, ILLINOIS, ASSIGNOR TO ROCKFORD TOOL COMPANY, OF ROCKFORD, ILLINOIS, A CORPORATION OF ILLINOIS.

RUBBING-MACHINE.

1,238,062.

Specification of Letters Patent. Patented Aug. 21, 1917.

Application filed December 22, 1916. Serial No. 138,495.

To all whom it may concern:

Be it known that I, GUSTAF H. EKSTROM, a citizen of the United States, residing at Rockford, in the county of Winnebago and 5 State of Illinois, have invented certain new and useful Improvements in Rubbing-Machines, of which the following is a specification.

This invention relates to machines for 10 rubbing or polishing plane surfaces and particularly to portable machines of this class intended for use in rubbing and polishing the varnished surfaces of woodwork.

One of the objects of this invention is to 15 produce a machine of the class described which shall be of sufficiently small and compact construction to permit its use in rubbing and polishing the comparatively narrow depressed surfaces that occur in paneled woodwork.

Another object of the invention is to simplify and cheapen the construction while preserving a high degree of efficiency and durability.

25 In the accompanying drawings, Figure 1 is a view (largely in section) of a portable rubbing machine embodying the features of my invention. Fig. 2 is a vertical transverse sectional view taken in the plane of dotted line 2—2 of Fig. 1. Fig. 3 is a fragmental transverse view on dotted line 3—3 of Fig. 1. Fig. 4 is a fragmental detail view.

The embodiment herein shown of this 35 invention comprises a body 1, a handle 2 rigidly secured to the body, a reciprocating structure supported by the body, and a rubbing pad secured to said reciprocating structure.

40 The body 1 is tubular and cylindrical, save that the lower side thereof is cut away as indicated in Figs. 2 and 3. The handle 2 is rigidly connected to the body midway of the length of the body and projects upwardly therefrom. Within the body 1 is a cylindrical tubular element 3 extending axially of the body. The inner end of the handle 2 is reduced in diameter and is screw-threaded to engage a screw-threaded 45 opening 4 in the element 3. The element 3 is spaced away from the body 1 by means of a curved plate 5. It will be evident from 50 Fig. 1 that the handle 2 serves to secure the

body 1, the element 3 and the spacer plate 5 rigidly together. 55

A tube 6 fits slidably within the body 1 and surrounds the element 3. Said element fits snugly within the tube. The plate 5 serves to prevent relative rotation between the body 1 and the tube 6. The tube has an elongated opening 7 therein to accommodate the spacer plate 5, the opening 7 being of sufficient length to allow reciprocation of the tube 6 within the body 1. The ends of the tube 6 are closed by means of heads 8 and 9 which are held in place by means of a rod or stem 10 extending axially of the tube 6, the ends of said rod being threaded to receive nuts 11. The opposite end portions of the tube 6 constitute reciprocating power cylinders, the ends of the tubular element 3 serving as stationary pistons in said cylinders. 70

The middle portion 12 of the rod 10 is of greater diameter than the end portions 75 of said rod, thus forming annular shoulders 13 and 14 on the rod. In the ends of the tubular element 3 are secured bushings 15 which are of less internal diameter than the tubular element 3, the inner ends of the bushings 15 thus forming annular shoulders 16 and 17. The openings through the bushings 15 constitute ports through which pressure fluid flows from the central chamber 3^a of the tubular element to the cylinders. 80 Suitable pressure fluid, as for example, compressed air, is admitted to the interior chamber 3^a of the tubular element 3 by suitable means, as, for example, by providing a passage 18 extending axially of the handle 90 2. The outer end of the passage 18 is arranged to communicate with the source of supply by means of a flexible tube (not shown).

The portion 12 of the rod 10 is of greater 95 length than the distance between the shoulders 16 and 17. The rod 10 is adapted to fit snugly within the bushings 15.

It will be seen that the shoulders 13 and 16 constitute coöperating valves to control 100 the flow of pressure fluid to the left-hand power cylinder and that the shoulders 14 and 17 form another pair of coöperating valves to regulate the flow of air to the right-hand cylinder. 105

In the lower side of the tube 6 are formed

two sets of exhaust ports 19, one set for each power cylinder. The end portions of the tubular element 3 constitute valves to close communication with the atmosphere 5 through the exhaust ports.

The rubbing or polishing element may be of any suitable or preferred construction. Herein is shown a bracket 20 having perforated ears 21 through which the rod 10 extends, said ears being clamped against the heads 8 and 9 by means of the nuts 11. The bracket 20 comprises a flange or web 22 to which a block 23 of wood or other suitable material is secured by means such as bolts 15 24. The block 23 is provided with a rubber face 25. 26 is a strip of felt or other suitable friction material which is secured over the face 25 by suitable means, as, for example, the nails 27. In the lower side of the 20 body 1 is a longitudinal slot 28 through which the ears 21 move.

Assuming the parts to be in the position shown in Fig. 1, the operation is as follows: Compressed air flows from the central chamber 3^a of the tubular element 3, past the annular shoulder 17 and along the rod 10 to the right-hand power cylinder. The tube 6 is thereby caused to move toward the right. As soon as the shoulder 14 reaches the shoulder 17, the flow of air to the right-hand cylinder is cut off, but the expansion of the air contained in said cylinder causes continuing movement of the tube 6. A moment before the shoulder 13 reaches the shoulder 16, one of the exhaust ports 19 passes the right-hand end of the tubular element 3, thus permitting exhaust of the air from the right-hand cylinder to commence. As soon as the shoulder 13 has passed the shoulder 16, compressed air flows from the central chamber 3^a to the left-hand cylinder, consequently as soon as the momentum of the tube 6 can be overcome said tube begins to move toward the left. The supply of compressed air to the left-hand cylinder is cut off as soon as the shoulder 13 reaches the shoulder 16 in the left-hand movement of said cylinder. The tube 6 is thus rapidly reciprocated, carrying with it the pad 26. The pressure of the air contained in the power cylinders prevents the heads 8 and 9 from striking the ends of the tubular element 3.

In practice the operator grasps the handle 2 and slides the machine over the surface to be rubbed or polished. While the machine is being thus moved, the tube 6 and its attached pad 26 are rapidly reciprocated to rub or polish the surface against which the pad is pressed, suitable abrasive or polishing material being placed upon said surface.

It will be evident that the machine herein disclosed is of very simple construction and comprises very few moving parts.

I claim as my invention:

1. A portable rubbing or polishing ma-

chine having, in combination, a body, a tube slidably supported by the body, the ends of the tube being closed, a piston-forming element within the tube and secured to the body, said element having internal annular shoulders near its ends, a rod extending from end to end of the tube and through said element, the ends of said rod being of reduced diameter to provide two annular shoulders on the rod adapted to coact with the shoulders in the tubular element, the distance between the shoulders on the rod being greater than that between the shoulders in the tubular element, means for admitting pressure fluid to the interior of the tubular element, exhaust means for the tube, and rubbing means actuated by the tube.

2. A portable rubbing or polishing machine having, in combination, a tubular body, a tube slidably mounted within the body, said tube having closed ends, a tubular element located within said tube and secured to the body, valve parts in the ends of said tubular element, co-operating valve parts extending through said tubular element and secured to the tube, means for supplying pressure fluid to the interior of said tubular element, and a rubbing element secured to said tube.

3. A portable rubbing or polishing machine having, in combination, a body, a tube slidably supported by the body, said tube having closed ends, a tubular element located within said tube and secured to the body, valve parts in the ends of said tubular element, co-operating valve parts extending through said tubular element and secured to the tube, means for supplying pressure fluid to the interior of said tubular element, the end portions of said tube having exhaust ports which are arranged to be covered by said tubular element, and a rubbing element secured to said tube.

4. A portable rubbing or polishing machine having, in combination, a tubular body, two cylinders slidably mounted within the body and having heads, a tubular element within said cylinders and secured to the body, the ends of said element constituting pistons which are opposed to the cylinder heads, means for admitting pressure fluid to the interior of the tubular element, means for controlling the flow of pressure fluid to and from the cylinders, and rubbing means actuated by said cylinders.

5. A portable rubbing or polishing machine having, in combination, a tubular body, two cylinders rigidly secured together and slidably mounted within the body and having heads, a tubular element within said cylinders and secured to the body, the ends of said element constituting pistons which are opposed to the cylinder heads, means for admitting pressure fluid to the interior of the tubular element, means for controlling

- the flow of pressure fluid to and from the cylinders, and rubbing means actuated by said cylinders.
6. A portable rubbing or polishing machine having, in combination, a tubular body, two cylinders rigidly secured together and slidably mounted within the body, a tubular element within said cylinders and secured to the body, the ends of said element constituting pistons, means for admitting pressure fluid to the interior of the tubular element, a valve member connected to the cylinders and extending through the tubular element, coöperating valve members in the tubular element, said cylinders having exhaust ports which are arranged to be closed by the tubular element, and rubbing means actuated by said cylinders.
7. A portable rubbing or polishing machine having, in combination, a tubular body, two cylinders rigidly secured together and slidably mounted within the body, a tubular element within said cylinders and secured to the body, the ends of said element constituting pistons, means for admitting pressure fluid to the interior of the tubular element, a valve member connected to the cylinders and extending through the tubular element, valve members in the tubular element, said cylinders having exhaust means, and rubbing means actuated by said cylinders.
8. A portable rubbing or polishing machine having, in combination, a tubular body, two cylinders rigidly secured together and slidably mounted within the body, a tubular element within said cylinders and secured to the body, the ends of said element constituting pistons, means for admitting pressure fluid to the interior of the tubular element, a rod extending from end to end of the cylinders and axially through the tubular element, the rod being fixed to the cylinders, valve members for the end portions of the tubular element, coöperating valve parts on the rod, said cylinders having exhaust means, and rubbing means actuated by said cylinders.
9. A portable rubbing or polishing machine having, in combination, a tubular body, two cylinders rigidly secured together and slidably mounted within the body, a tubular element within said cylinders and secured to the body, the ends of said element constituting pistons, means for admitting pressure fluid to the interior of the tubular element, a rod extending from end to end of the cylinders and axially through the tubular element, said rod being fixed to the cylinders, valve members for the end portions of the tubular element, coöperating valve parts on the rod, said cylinders having exhaust ports which are arranged to be closed by the tubular element, and rubbing means actuated by said cylinders.

10. A portable rubbing or polishing machine having, in combination, a body, two cylinders rigidly secured together and slidably supported by the body, a tubular element within said cylinders and secured to the body, the ends of said element constituting pistons, means for admitting pressure fluid to the interior of the tubular element, means for controlling the flow of pressure fluid to and from the cylinders, and rubbing means actuated by said cylinders.

11. A portable rubbing or polishing machine having, in combination, a body, two reciprocating cylinders supported by the body, heads secured to the remote ends of said cylinders, pistons in said cylinders supported by the body, valve means for said cylinders, and a rubbing element attached to the cylinders.

12. A rubbing or polishing machine having, in combination, a pair of cylinders rigidly connected together, a pair of pistons for the cylinders, said pistons being rigidly connected together, means to prevent relative turning movement between said pairs of elements, one of said pairs of elements having a central chamber provided with aligned ports communicating with the cylinders, a rod fixed to the other pair of elements and extending into said chamber, said rod having portions constituting valves that control the flow of pressure fluid through said ports to the cylinders, and rubbing means actuated by one of said pairs of elements.

13. A portable rubbing or polishing machine having, in combination, a body, a pair of cylinders rigidly connected together, a pair of pistons for the cylinders, said pistons being rigidly connected together, pressure-fluid-controlling means for the cylinders, a handle secured to the body and to one of said pairs of elements, and a rubbing element rigidly attached to the other of said pairs of elements.

14. A portable rubbing or polishing machine having, in combination, two reciprocating cylinders rigidly secured together, a piston-forming element in said cylinders, valve means in said element, coöperating valve means attached to said cylinders, means for admitting pressure fluid to the interior of said element, and rubbing means actuated by said cylinders.

15. A portable rubbing or polishing machine having, in combination, a body, two reciprocating cylinders rigidly secured together, a piston-forming element in said cylinders secured to said body, valve means in said element, coöperating valve means attached to said cylinders, and rubbing means actuated by said cylinders.

16. A portable rubbing or polishing machine having, in combination, two reciprocating cylinders rigidly secured together, a

piston-forming element in said cylinders, valve means in said element, coöperating valve means attached to said cylinders, means for admitting pressure fluid to the 5 interior of said element, and a rubbing element rigidly attached to said cylinders.

17. A portable rubbing or polishing machine having, in combination, a body, two reciprocatory cylinders rigidly secured together, means to prevent relative rotation between the body and the cylinders, pistons in said cylinders rigidly secured to said body, a handle secured to the body, said handle having a fluid supply passage communicating with the space between the pistons, valve means for said cylinders, and rubbing means actuated by said cylinders.

18. A portable rubbing or polishing machine having, in combination, a body, two reciprocatory cylinders rigidly secured together, a piston-forming element in said cylinders secured to said body, a handle secured to the body, said handle having a fluid supply passage communicating with 25 the interior of said element, valve means in said element, coöperating valve means attached to said cylinders, and rubbing means actuated by said cylinders.

19. A rubbing or polishing machine having, in combination, a pair of cylinders rigidly connected together, a pair of pistons for the cylinders, said pistons being rigidly connected together, means to prevent relative turning movement between 30 said pairs of elements, one of said pairs of elements having a central chamber, a rod

fixed to the other pair of elements and extending into said chamber, said rod having portions constituting valves that control the flow of pressure fluid from said chamber to the cylinders, and rubbing means actuated by one of said pairs of elements.

20. A portable rubbing or polishing machine having, in combination, a pair of cylinders rigidly connected together, a pair of 40 pistons for the cylinders, said pistons being rigidly connected together and having a central chamber, means to prevent relative turning movement between said pairs of elements, means for admitting pressure fluid to 45 the central chamber, means for controlling the flow of pressure fluid from said chamber to the cylinders, and a rubbing element rigidly attached to one of said pairs of elements.

21. A rubbing or polishing machine having, in combination, a pair of cylinders rigidly connected together, a pair of pistons for the cylinders, said pistons being rigidly connected together, means to prevent relative turning movement between said pairs of elements, one of said pairs of elements having a central chamber with means for admitting pressure fluid to said chamber, means controlling the flow of pressure fluid 50 from said chamber to the cylinders, and rubbing means actuated by one of said pairs of elements.

In testimony whereof, I have hereunto set my hand.

GUSTAF H. EKSTROM.
